No. 36,779.

Patented February 9, 1904.

UNITED STATES PATENT OFFICE.

FREDERICK J. KNORR AND ALICE S. KUHN, OF BLOOMINGTON, ILLINOIS.

DESIGN FOR A SPOON.

SPECIFICATION forming part of Design No. 36,779, dated February 9, 1904.

Application filed November 10, 1903. Serial No. 180,624. Term of patent 3½ years.

To all whom it may concern:

Be it known that we, FREDERICK J. KNORR and ALICE S. KUHN, citizens of the United States, residing at Bloomington, in the county of McLean and State of Illinois, have invented a new, original, and ornamental Design for Spoons, of which the following is a specification, reference being had to the accompanying drawing, forming part thereof.

The figure is a plan view of a spoon, showing our new design.

We claim as new and desire to secure by Letters Patent—
The ornamental design for a spoon as herein shown.

FREDERICK J. KNORR.
ALICE S. KUHN.
